UNITED STATES PATENT OFFICE.

JOSEPH B. EATON AND GEORGE CASH, OF PHILADELPHIA, PENNSYLVANIA;
SAID CASH ASSIGNOR TO HARRY KEEL, OF BROOKLYN, NEW YORK.

INDICATOR FOR GAS-COCKS.

SPECIFICATION forming part of Letters Patent No. 340,495, dated April 20, 1886.

Application filed October 17, 1885. Serial No. 180,138. (No model.)

To all whom it may concern:

Be it known that we, JOSEPH B. EATON and GEORGE CASH, both citizens of the United States, residing in the city and county of Philadelphia, State of Pennsylvania, have invented a new and useful Improvement in Gas-Supply Regulators, which improvement is fully set forth in the following specification and accompanying drawings, in which—

10 Figure 1 represents a front view of a gas-supply regulator embodying our invention. Fig. 2 represents a rear view of a detached portion thereof on an enlarged scale. Fig. 3 represents a section thereof in line xx , Fig. 2.
15 Fig. 4 represents a plan view of a detached portion thereof.

Similar letters of reference indicate corresponding parts in the several figures.

Our invention consists of a device for regulating or controlling the supply of gas to the place of service, the same being conveniently operated and reliable in action, and possessing other advantages, as will be hereinafter fully set forth.

25 Referring to the drawings, A represents a dial, which is fitted with a case, B; and C represents an index, finger, or pointer, which is connected with a grooved pulley or disk, D, the latter being mounted on plates D' D², attached to the case B at the rear of the dial, said index sweeping over the face of the dial.

30 E represents the gas-cock, which is connected with the gas-meter or inlet-pipe thereof in any suitable manner; and F represents the key of said cock, the same being fitted at top in a step or socket, G, which is secured to the ceiling of the cellar, whereby the key is properly sustained and prevented from lateral displacement. To the key is attached a 35 grooved wheel or pulley, H, the hub H' whereof is provided with screws or bolts J, whereby the pulley may be firmly secured to the key.

40 Running around the pulleys D and H is an endless cord, band, or strap, K, the same passing through openings in the floor or ceiling and around guide-pulleys L, suitably applied. The pulley D has an opening or socket, M, in its periphery, to receive a bar or handle, N, for rotating said pulley, it being noticed that 45 when said handle is inserted in the socket M it occupies a position between the plates D' D², and projects from the periphery thereof so

as to be readily grasped. When the handle is removed, it will be seen that the socket M or the periphery of the pulley D cannot be 55 reached by the fingers in order to tamper with said pulley, as the space between the two plates D' D² around the periphery of the pulley is narrow, while the inner faces of the main portions of said plates are recessed to receive said 60 pulley. The dial A is graduated or marked with the number of burners and the words “full” and “off,” so that by rotating the pulley D until the index C sets at the desired place the motion is communicated by the belt 65 K and pulley H to the gas-cock, and thus the supply of gas is regulated so as to be at full head, entirely cut off, or at intermediate points. The rear plate, D', is provided with openings 70 P, in order to hang the casing and connected parts on a nail, hook, pin, &c.; but it is evident that the same may be set in a wall, and the belt covered in any suitable manner so as to prevent improper handling thereof. When the key is not required, the pulley H may be 75 fitted directly to the gas-cock.

Having thus described our invention, what we claim as new, and desire to secure by Letters Patent, is—

1. In a gas-regulator, a dial in combination 80 with a grooved disk or pulley connected therewith, and recessed plates D' D², which form the bearings for said pulleys and inclose the same, the periphery of the pulley having a socket, and the plates having at their rim a 85 narrow opening to receive the handle N, which is adapted to be inserted into the socket M, substantially as and for the purpose set forth.

2. A gas-regulator composed of the following parts: the grooved disk D, having the 90 socket M in its periphery, the recessed plates D' D², with a space between their rims, index C, secured to said disk, handle N, adapted to be inserted in said socket M, a dial, the casing B, endless belt K, and key F, having 95 pulley H mounted thereon, all of said parts being arranged, combined, and operated substantially as described.

JOS. B. EATON.
GEORGE CASH.
